UNITED STATES PATENT OFFICE.

JASPER NOLEN MANLEY AND PAUL YOUREE ISBELL, OF MEMPHIS, TENNESSEE.

LETTER AND PAPER HOLDER.

Application filed March 22, 1923. Serial No. 626,913.

To all whom it may concern:

Be it known that we, JASPER NOLEN MANLEY and PAUL Y. ISBELL, citizens of the United States, residing at Memphis, in the county of Shelby and State of Tennessee, have invented certain new and useful Improvements in Letter and Paper Holders; and we do declare the following to be a full, clear, and exact description of the invention, such as will enable others skilled in the art to which it appertains to make and use the same.

Our invention relates to an improved letter and paper holder for use by typists, for the purpose of holding letterheads, follow sheets, and letters which have been type-written.

One object of the invention is to provide a device of the character set forth provided with a pair of vertically spaced shelves constituting the bottoms of a pair of pigeon holes, one of these holes being intended to receive letterheads while the other is for the reception of follow sheets, the construction being such as to facilitate easy removal of the top letterhead or follow sheet without disturbing the remainder of the pack. Thus, the typist may easily withdraw a letterhead or a follow sheet, or both.

Another object is to provide a receiving tray for completed letters or other work, provided with novel means for holding the sheets in place, so that there is no possibility of them blowing from the desk.

With the foregoing in view, the invention resides in the novel subject matter herein-after described and claimed, the description being supplemented by the accompanying drawing.

Figure 1 is a perspective view of a paper holder constructed in accordance with our invention.

Figure 2 is a longitudinal sectional view.

Figure 3 is a detail transverse sectional view on line 3—3 of Fig. 2.

In the drawing, above briefly described, the numeral 1 designates a suitable cabinet or container open at its front end and top but provided with parallel side walls 2 and

with a rear wall 3. A pair of horizontal shelves 4 are mounted between the side walls 2 and form the bottoms of a pair of pigeon holes, one of which is intended to contain letterheads while follow sheets may be inserted in the other, the front ends of said shelves preferably having notches 5. The rear ends of the pigeon holes are preferably formed by rearwardly declined boards, slats or the like 4^a. When the pigeon holes are filled with packs of paper and the rear edges of the sheets strike the members 4^a, the packs are so distorted that their front ends will be disposed in rearwardly declining planes. Thus, it will be seen that the uppermost sheet may be very conveniently removed by the typist, without in any manner disturbing the remainder of the pack.

Above the uppermost of the shelves 4, is another shelf 6 having a normally raised depressible front end section 7, constituting an operating member for paper holders yet to be described. The shelf 6 and the upper portions of the walls 2 and 3 define a tray adapted to contain completed letters or other sheets of paper and it will be seen that while we have shown this tray in connection with pigeon holes for letterheads and second sheets, such a tray might well be used independently of these pigeon holes.

A pair of vertically movable paper holding arms 8 are pivotally carried by the tray, one of these arms being preferably located at each side of the tray, as illustrated. However, it will be understood that in some instances only one of the arms might be used. Each of the arms 8 is provided with a rubber head or the like 9 for anti-slipping engagement with the paper and means are provided whereby this head is held tightly down. Means are also provided, however whereby depression of the front shelf section or operating member 7, will raise the arms to permit a sheet of paper to be inserted or removed, as required.

In the present disclosure, the arms 8 are carried by the rear ends of a pair of rock shafts 10 which are rotatably carried by the sides of the tray, the front ends of said

rock shafts having crank arms 11 which extend oppositely from the arms 8 and are connected by links 12 with the operating member 7. In the preferred form of construction, the parts 8, 10 and 11 are formed by bending wire in the manner shown and the pivotal connections between the links 12 and the arms 11 are established by bending suitable eyes 13 therein. In connecting the lower ends of the links 12 with the operating member 7, we prefer to secure a length of wire 14 to the lower side of said member, extending the ends of this wire forwardly and laterally and connecting them with the links by interengaged eyes 16.

In the preferred form of construction, coil springs 17 are wound around the rock shafts 10 for turning them in such a manner as to swing the arms 8 normally downward and we prefer to groove the inner opposed sides of the tray as indicated at 18 to receive said springs and shafts. Appropriate bearings 19 may be inset in widened portions 20 of the grooves 18 and these bearings may well be formed by winding strips of metal as shown in Fig. 3. For retaining the shafts 10 and associated parts in proper position upon the sides of the tray, wooden strips 21 may be secured to said sides and grooved wherever necessary, said strips being formed with notches 22 in which the arms 8 may swing.

By providing a device constructed in the manner shown and described, or in a similar manner, a device is provided which will be highly efficient and desirable for the purposes intended. A letterhead and a second sheet may be withdrawn from the cabinet in a single operation for the writing of a letter or the like and when the work is completed, it is simply necessary to depress the shelf section or operating member 7, thereby swinging the arms 8 upwardly to the dotted line position shown in Fig. 1. Then, the work may be inserted in the tray and when pressure upon the member 7 is relieved, the arms 8 will descend and hold the sheets of paper in place.

As excellent results may be obtained from the details disclosed, these details may well be followed. However, within the scope of the invention as claimed, numerous minor changes may be made, for instance in the number of pigeon holes used and the general design and appearance of the device.

We claim:

1. A paper holding device comprising a tray to receive sheets of paper, said tray having a permanently open front end, a vertically movable self-lowering paper holder mounted to hold sheets of paper on the tray bottom, a substantially horizontal operating member at said open front of the tray normally forming a continuation of the tray bottom and movable downwardly from its

normal position, and connecting means between said paper holder and said operating member for raising the former when the latter is depressed from its normal substantially horizontal position.

2. A paper holding device comprising an open ended tray, a rock shaft extending along one side of said tray and having a paper holding arm, means for turning said rock shaft and holding said paper holding arm in an operative position, and means whereby said shaft may be turned to raise said paper holding arm.

3. A paper holding device comprising an open ended tray, a rock shaft extending along one side of said tray and having a paper holding arm, a depressible operating member at the open end of said tray, and connecting means between said operating member and said rock shaft for turning the latter to raise said paper holding arm.

4. A structure as specified in claim 3, said connecting means comprising a crank arm on the rock shaft and linkage connecting said crank arm with said operating member.

5. A paper holding device comprising an open ended tray to receive sheets of paper, said tray having a depressible operating member at its open end, a rock shaft extending along one side of said tray, said rock shaft having a paper holding arm and having a crank arm at its front end, a link depending from said crank arm at the front end of the tray, a duplicate of said rock shaft, paper holding arm, crank arm and link at the opposite side of the tray, and a length of wire secured to said operating member and having outwardly bent ends connected with the lower ends of said links.

6. A paper holding device comprising a tray having a longitudinal groove in the inner face of one of its side walls, a rock shaft and a rotating spring therefor confined in said groove, the outer end of said shaft having means whereby it may be turned against the action of said spring, a paper holding arm extending from the inner end of said rock shaft, and a strip secured to said side of the tray and retaining said spring and rock shaft in said groove.

7. A structure as specified in claim 6, said groove having widened portions, and bearings for said rock shaft received in said portions.

8. A typist's holder for letterheads, second sheets and completed work, comprising a horizontally disposed cabinet having two opposed vertical side walls and a vertical back wall, a shelf secured between the lower portions of said side walls to support letterheads, a second shelf secured between said side walls above the first shelf to support second sheets, and a third shelf above said first and second shelves, said third shelf being secured between said side walls in down-

wardly spaced relation with the upper extremities of the side and back walls, said third shelf co-operating with the upper portions of said side and back walls in forming 5 an open-topped tray for completed work, the space between the aforesaid side walls at the front ends of the shelves, being entirely

open for insertion and removal of the sheets to be supported thereby.

In testimony whereof we have hereunto ¹⁰ affixed our signatures.

JASPER NOLEN MANLEY.
PAUL YOUREE ISBELL.
